ARTHUR WILLIAM PURCHAS, OF YORK, ENGLAND.

EDUCTION-PIPE FOR AIR-LIFT PUMPS.

1,291,130.

Specification of Letters Patent. Patented Jan. 14, 1919.

Application filed September 29, 1915. Serial No. 53,162.

To all whom it may concern:

Be it known that I, ARTHUR WILLIAM PURCHAS, a subject of the King of Great Britain, and a resident of Westow, Kirkham 5 Abbey, York, England, have invented a new and Improved Eduction-Pipe for Air-Lift Pumps, of which the following is a full, clear, and exact description.

My invention relates to eduction pipes for 10 air-lift pumps, and the object thereof is to provide a simple and inexpensive pipe whereby the efficiency of the lift pump is greatly increased by reducing the loss by high-entrance velocity and contracted water 15 passageways.

With the above and other objects in view, the nature of which will more fully appear as the description proceeds, the invention consists in the novel construction, combination 20 and arrangement of parts as herein fully described, illustrated and claimed. In the accompanying drawings, forming part of the application, similar characters of reference indicate corresponding parts in all 25 the views.

Figure 1 is a diagrammatic view of a lift pump having an eduction pipe embodying my invention;

Fig. 2 is a slightly modified form thereof; 30 and

Fig. 3 is a diagram for explaining the reasons for the reduction in sectional area of the eduction pipe above the water level of the well or container where the eduction 35 pipe is used.

Prior to air being injected into the eduction pipe, the water surface inside the pipe will stand at the same level as that outside, that is, at A A, Fig. 3, and the pressure on 40 the upper and lower sides of the plane X X will be equal. The injection of an air bubble into the eduction pipe must necessarily displace a volume of water equal to the volume of the air bubble; and since the bottom of 45 the eduction pipe is open, the pressure on the two sides of the plane X X will readjust itself to equality if disturbed. The weight of the bubble of air injected being negligible, the volume of water which it displaces 50 must move upward within the eduction pipe in order that the balance of weights or pressures on the two sides of the plane X X shall be maintained; and consequently the

water surface inside the eduction pipe will be raised above the water surface A A by an 55 amount equal to $\frac{v}{a}$, where v is the volume of the air bubble and a the cross sectional area of the eduction pipe. The air bubble then rises through the volume of water, and 60 finally escapes into the atmosphere. The important point is that there is no loss by slip, of the energy originally contained in the air bubble until it breaks the surface of the liquid in the eduction pipe. Let l be 65 the lift in feet, and h the head in feet numerically equal to $\frac{v}{a}$. If sufficient air be introduced into the eduction pipe, the head h will finally exceed the lift l , and then a 70 volume of water equal to $ah - al$ will be discharged from the top of the eduction pipe. The loss of this weight of water from the eduction pipe will produce an unbalanced head equal to $h - l$ on the under 75 side of the plane X X, Fig. 3; and, therefore, this head $h - l$ will cause more water to flow into the eduction pipe.

Experiments have shown that a large proportion of this head is wasted in forcing 80 water into the space inside the eduction pipe which is not already occupied by air. To eliminate this waste, the eduction pipe 4 has the cross-sectional area of the part 5, which is immersed into the water, as large 85 as permitted by the well or container in which the pipe is positioned, therefore the losses due to high velocity and contracted water passageways will be reduced, while the loss by slip in this length of pipe will 90 be negligible, as can be seen from the theoretical discussion previously given.

It is evident that enough space must be left about the portion of the eduction pipe which is submerged to facilitate the flow of 95 water to the eduction pipe. At a point near the pumping level, that is, A A (Figs. 1 and 2), the loss by slip will begin to need consideration; and, to keep this loss within reasonable limits, the cross-sectional area 100 of the eduction pipe must be so proportioned that the velocity of the rising mixture will be between certain limits. These limits will necessitate a reduced area for the pipe in all cases. The velocity of the rising mixture 105 in the eduction pipe per unit of time in-

creases as the outlet of the pipe is reached. If the eduction pipe is kept of uniform cross-sectional area above the liquid level A A, as shown at 6 in Fig. 2, the frictional losses may be excessive; and to overcome this, the cross-sectional area of the eduction pipe is increased uniformly or in steps, as shown in Fig. 1, 7 being the reduced portion above the water level A A, while 8 is the enlarged cross-sectional area above the reduced area 7. By properly varying the cross-sectional area of the eduction pipe above the liquid level A A, the minimum sum of the losses due to friction and to slip 15 is attained.

While I have described the principle of operation, together with the eduction pipe which I now consider to be the best embodiment thereof, I desire to have it understood 20 that the description and illustration

thereof are merely illustrative, and that such changes may be made as are within the scope of the appended claim.

I claim:

An eduction pipe for air lifts, the cross section of which varies in steps, the maximum cross section being at the bottom and adapted to be submerged, the minimum cross section following the maximum cross section, the section larger than the minimum 30 but smaller than the maximum following the minimum section.

In testimony whereof I have signed my name to this specification in the presence of two subscribing witnesses.

ARTHUR WILLIAM PURCHAS.
